Primary Examiner — Eric L Goodman*Assistant Examiner* — Sarah L Smith(74) *Attorney, Agent, or Firm* — Fitzgerald IP Law; John K Fitzgerald, Esq.(57) **CLAIM**

The ornamental design for a decoration base for toy beads, as shown and described.

DESCRIPTION

FIG. 1 is a perspective view of portions of the front, top, and left sides of a decoration base for toy beads showing my new design;

FIG. 2 is a perspective view of portions of the rear, bottom, and right sides thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof; and,

FIG. 9 is reference view of the decoration base for toy beads of FIG. 1 showing a horse figure drawn in broken lines. The broken lines shown are included for the purpose of illustrating portions of the article which form no part of the claimed design.
